[57] **CLAIM**

The ornamental design for fuse holder for automobiles, as shown and described.

DESCRIPTION

FIG. 1 is a perspective view of the design;
FIG. 2 is a rear elevational view thereof;
FIG. 3 is a front elevational view thereof;
FIG. 4 is a top plan view thereof;
FIG. 5 is a bottom plan view thereof;
FIG. 6 is a right side elevational view thereof;
FIG. 7 is a left side elevational view thereof; and,
FIG. 8 is a cross-sectional view taken along line 8—8 in FIG. 6.

The article of the present design is fuse holder for automobiles to protect electrical circuits, especially the main power supply, motor loads etc.
